H. M. KORETZKY

ELECTRIC LAMP AND SUPPORT THEREFOR

Filed Aug. 20, 1926

Inventor:

Harry M. Koretzky
By H. M. Koretzky
attorney.

UNITED STATES PATENT OFFICE.

HARRY M. KORETZKY, OF HOBOKEN, NEW JERSEY.

ELECTRIC LAMP AND SUPPORT THEREFOR.

Application filed August 20, 1926. Serial No. 130,506.

My present invention relates to a convenient form of self-contained electric lamp which can be taken apart so as to yield on the one hand a base capable of use as an ash tray 5 and on the other hand a portable flash light.

The invention also comprises certain preferred details of construction hereinafter fully described and set forth.

The invention is illustrated in a preferred 10 form by way of example in the accompanying drawings wherein Figure 1 is a view of the entire combination in elevation, Figure 2 is a similar view of the lamp base in position for use as an ash tray, Figure 3 is a view in longitudinal section of the upper and lower parts of the flashlight separated and Figures 4 and 5 are upper and lower plan views respectively of the preferred form of removable lamp-supporting disc.

20 The flash light proper is preferably constructed according to the principles of that well known type in which a metallic outer cylindrical casing carries the current and closes the circuit through the bulb when alight.

At 10 is shown the usual cylindrical outer casing, furnished at one end with a screw cap 11 carrying the usual reflector and lens, whereby, preferably, the focus of the light 30 may be adjusted at will in a well known manner.

Within the metal casing 10 are carried the usual group of battery cells, loosely assembled end to end and each covered with cardboard or other insulation in a manner well known. The zinc cup of each cell is bare at the bottom, and the carbon electrode 13 of 35 each cell touches the zinc bottom of the next above it.

40 The usual electric bulb 14 screws into a socket at the center of a bulb-supporting disc 15 whose periphery is threaded, as shown, so as to screw down into the threaded upper end 16 of the cylinder 10. Finger holds 17 are 45 bent upward from the flat surface of the disc 15 to facilitate screwing the disc down into place.

A spiral spring 18 is interposed between the disc 15 and the insulating seal that closes the 50 top of the uppermost battery cell 12. The pressure of this spring pushes the entire battery down against the metal cap 19 which 55 closes the lower end of the casing 10, being threaded thereon as clearly shown in the lower part of Figure 3.

When the lamp is unlighted, as shown in Figure 3, the carbon 13 does not touch the central terminal 20 of the bulb 14. By screwing the cap 19 further on, however, the battery is moved upward within the casing 60 10 until the carbon 13 touches the terminal 20, when circuit will be closed through the lamp bulb 14, in a well known manner, to light the same. Flashlights operated on this general principle are well known in this art, and the 65 same are not broadly claimed herein.

In Figure 1, the form of flashlight so far described is shown mounted upon a base, preferably comprising an inverted basin 21 furnished with a number of legs 22, preferably three as shown. These legs are stiff springs with flaring tips 23 to facilitate forcing down between them the lower end of the flashlight, so that it assumes the position shown in Figure 1, wherein the springs 22 70 closely embrace and grip the threaded cover 19 at the lower end of the flashlight.

75 There is thus constituted a standing electric lamp which can be instantly lighted or extinguished by simply turning the casing 80 slightly one way or the other. As the spring legs 22 hold the cover 19 fixed, this revolution of the casing 10 will cause the lamp bulb 14 to move up or down, as the case may be, thus opening or closing at will the contact at 20. 85

Upon removing the flash light by withdrawing the cover 19 from between the springs 22, the base may be inverted, as shown in Figure 2, and, standing upon the legs 22, 90 may be used as an ash tray.

95 While the threaded cover 19 may be constructed in any convenient manner to make possible the operation above set forth, I prefer the construction shown in the lower part of Figure 3 whereby the operation of the flash light, when separated from its base, may be carried out either, as above described by turning the cap 19 or in the manner about to be described.

The central portion of the cap 19 is spun 100 inward to form a tubular socket 24, within which plays a sliding button 25, pressed outward by a spiral spring 26 within the socket 24. The inner periphery of the button 25 is flanged outward to form a circular lip 27 105 which limits the outward movement of the button.

110 Now, by turning the cap 19 until the circuit is nearly closed at 20, the lighting of the lamp can be instantly accomplished by press-

ing inward on the button 24 and pushing the battery toward the bulb to make contact at 20. Thus the light becomes available for producing momentary flashes of light, as distinguished from producing a constant light, since mere removal of pressure by the thumb or finger on the button 24 will permit the spring 18 to break the circuit at 20 and extinguish the light.

10 While my broad invention is not necessarily confined to any particular mode of securing in place the spring 18, whereby the battery is normally pressed away from the bulb 14, one feature of my preferred form 15 comprises an improved structure for this purpose illustrated in Figures 3 to 5.

For this purpose a channel 28, semicircular in cross section is formed by pressure in the disc 15. This channel is concave downward and forms almost a complete circle.

20 At diametrically opposed points, however, the channel is interrupted by pressing two small portions 29, 30, downwardly as shown in Figure 5, thus forming two narrow retaining bands.

The diameter of the circle described by the channel 28 is the same as that of the spiral of the spring 18, and this latter is held in place by inserting one end thereof under one of the 30 bands 29 or 30, and turning the spring so

that its terminal convolution 31 passes under both bands and occupies the channel 28. This is plainly shown in Figures 3 and 4.

Various changes may be made in the construction of my improved lamp, and I do not limit myself to the details shown and described.

What I claim is—

1. A self-contained electric lamp having an external casing and a terminal threaded cap having means to control the lamp circuit by relative rotatory movements of said casing and cap; in combination with an empty bowl-shaped base having springs adapted to receive said cap between them with a firm gripping pressure, said springs being adapted to afford a stable support for the base when the latter is inverted.

2. In a self-contained electric lamp, an outer casing, a movable battery therein, a spring at the top of the battery tending to push the same out of operative contact, a cap at the rear end of the casing, a short central tube extending inwardly on said cap, a spiral spring in said tube, and a hollow cup within said spring engaging the same and adapted to operate as a push button.

In testimony whereof I have hereto affixed my signature on this 29th day of July, 1926.

HARRY M. KORETZKY.
